(57) **CLAIM**

The ornamental design for a vehicle light, as shown and described.

DESCRIPTION

FIG. 1 is a perspective view of the first component of a vehicle light showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the second component of the vehicle light;

FIG. 10 is another perspective view thereof;

FIG. 11 is a front elevation view thereof;

FIG. 12 is a back elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is an enlarged view of the encircled portion in FIG. 10; and,

FIG. 18 is a perspective view of the vehicle light.

The equal-length broken lines depict portions of the vehicle light that form no part of the claimed design.

The dash-dot broken lines in FIG. 10 and FIG. 17 illustrate the boundaries of the enlarged view indicators and form no part of the claimed design.

1 Claim, 18 Drawing Sheets
